UNITED STATES PATENT OFFICE.

JOEL T. HART, OF SAN ANTONIO, TEXAS.

SASH-HOLDER.

1,162,860.

Specification of Letters Patent. Patented Dec. 7, 1915.

Application filed May 8, 1911. Serial No. 625,904.

To all whom it may concern:

Be it known that I, JOEL T. HART, a citizen of the United States, residing at San Antonio, in the county of Bexar and State 5 of Texas, have invented certain new and useful Improvements in Sash-Holders, and do hereby declare that the following is a full, clear, and exact description of the same, reference being had to the annexed drawings, making a part of this specification, and to the letters and figures of reference marked 10 thereon.

My invention relates to sash holders of the kind for which I obtained United States 15 patent, February 18, 1896, and the object of my invention is to so change the construction of said patented sash holder as to simplify, cheapen and otherwise improve the same.

20 With this object in view, my present invention consists in the sash holder constructed substantially as hereinafter specified and claimed.

In the accompanying drawings—Figure 25 1 is a perspective view of a portion of a window with my sash holder showing position for use; Fig. 2 is a vertical section thereof on a plane at right angles to the axes of the levers; and Fig. 3 a section 30 on line 3—3 of Fig. 2.

As in the case of my previously patented sash holder, I employ two reversed but otherwise similar cam carrying levers 10, each having a handle 11 on one side of its 35 pivot and on the other side of its pivot having a cam 12 with a roughened face adapted to engage the edge of the window bead 13, or if preferred, a corrugated or roughened strip of metal 14 fastened thereto to avoid 40 wear of the wooden bead. The cam members of both levers are yieldingly pressed toward each other and against the window bead by means of a spring consisting of a coil 15 having two tangentially extending 45 arms 16, each of which arms engages the cam member of a lever which is notched or slotted to receive the spring arm so that the latter is prevented from sidewise or lateral movement and thus in that regard 50 is maintained in a fixed position laterally with reference to the lever. The spring with its two arms, it will be seen, is V-shaped. Both the levers are pivoted on the same tube or thimble 17 and the coil of the 55 spring is also placed thereon, a rivet 18 passing through the tube or thimble and

through the opposite walls of the casing securing the same in position.

The coil is superimposed above and upon the levers, and therefore in the order of 60 assembling the parts is placed on the thimble last, or after the levers are in place, which enables the spring arms to be readily turned into a state of tension, and then set into engagement with the levers, after which 65 the cover plate of the casing may easily be mounted on the base plate and rivet, thus securing all the parts in place. Also by 70 this construction the tension of the spring arms may be so adjusted with relation to the coil that they will exert slight pressure upon the levers to hold them against the base plate and corresponding reaction of 75 the coil against the cover part of the case, which will prevent rattling or shaky action 80 of the levers in the case, without imposing material friction on the parts, the frictional surface of the spring being confined to the area close to the axis of the parts with consequent reduction of movement.

It will thus be seen by the employment 85 of a single element for pivoting the levers, mounting a spring and connecting the opposite walls of the casing together, I produce a most simple, inexpensive, compact 90 and yet wholly efficient device. The casing consists simply of two strips of sheet metal, a simple straight piece 19 that forms the base and which goes next to the sash bar when the holder is applied to the sash, and 95 the other a strip of sheet metal 20 which is bent down at one edge to form a flange 21 that constitutes a side wall of the box or casing, it being notched for the play of the levers, and which is also similarly bent at 100 each end to form top and bottom walls and is again bent parallel with the piece or strip 19 to form a foot through holes in which and holes in the strip 19 screws are passed to attach the device to the window. 105 Said attaching screws by reason of their location can be short screws and they can easily be applied. The casing being formed of sheet metal as I have described, especially by reason of the presence of the side 110 forming flange 21, is not only neat looking but it is very strong. It is desirable to limit the extent of the movement of the levers and the spring arms, and thus prevent likelihood of breakage of the spring 115 by excessive movement. I provide for this in a very simple manner by striking up

from the base piece or strip 19 a tongue or lug 22 in position to engage each lever at the desired limit of movement, there being a stop lug or tongue for each lever.

5 By my new construction I am able to space the box or casing plates 19 and 20 sufficiently far apart to avoid any rubbing of the spring arms on the box sides, and thus friction is avoided, which in practice 10 has been found objectionable in that it renders hard the operation of moving the levers to free the cams from engagement with the window frame. Again the cams are inclosed except for the slight protrusion 15 necessary to give them a grip on the bead, and thus danger of the cams and the free ends of the spring arms catching into and tearing lace curtains and injuring the hands is obviated.

20 Having thus described my invention what I claim is—

A sash holder having a box or casing formed of two sheet metal members one of which is a flat straight piece and the other 25 of which is bent toward the flat straight piece to form a side wall and top and bottom walls, said flat straight piece projecting beyond said top and bottom walls, and each projecting portion being overlapped 30 by an outturned foot extending from the contiguous end wall, said foot and the over-

lapped portion of the flat straight piece having alining holes for the reception of a fastening screw, a pair of cam carrying levers pivoted between said members, a double arm spring having a coil from which arms extend and engage the levers, a rivet 35 securing said sheet metal members together at a point substantially midway between the top and bottom walls of the casing and constituting the pivot for both said levers, the two levers overlying one another at the pivot and each lever being crossed by one of the spring arms where it extends from the coil to the point of engagement of the 40 spring arm with its lever, and the lever at the point of engagement having a notch which receives the outer end portion of said spring arm, the coil of the spring being mounted on said pivot, above and superimposed upon the levers with compressive 45 tension exerted between the levers and case plate to seat the levers against the straight flat base piece of the case, and a stop for each lever consisting of a tongue struck up 50 from said straight flat piece.

In testimony whereof I affix my signature in presence of two witnesses.

JOEL T. HART.
